(57) **CLAIM**

The ornamental design for protective guard for a lock picking device as shown and described.

DESCRIPTION

FIG. 1 is a top, front perspective view of a protective guard for a lock picking device showing my new design;
FIG. 2 is a bottom, rear perspective view thereof;
FIG. 3 is a top plan view thereof;
FIG. 4 is a bottom plan view thereof;
FIG. 5 is a side elevational view thereof;
FIG. 6 is a front elevation view thereof;
FIG. 7 is a rear elevation view thereof; and,
FIG. 8 is a perspective view of the protective guard in-use with an unclaimed lock picking device.
The broken line depiction of lock picking device in FIG. 8 is provided for purposes of environment and forms no part of the claimed design.
